UNITED STATES PATENT OFFICE.

ANDREW J. TEWKSBURY, OF HAVERHILL, MASSACHUSETTS.

LEATHER-SKIVING MACHINE.

SPECIFICATION forming part of Letters Patent No. 439,208, dated October 28, 1890.

Application filed May 4, 1889. Serial No. 309,632. (No model.)

To all whom it may concern:

Be it known that I, ANDREW J. TEWKSBURY, of Haverhill, county of Essex, State of Massachusetts, have invented an Improvement 5 in Leather-Skiving Machines, of which the following description, in connection with the accompanying drawings, is a specification, like letters on the drawings representing like parts.

10 This invention has for its object to improve the construction of leather-skiving machines—such, for instance, as shown in United States Patent No. 273,931, granted to Christopher Amazeen March 13, 1883—and has 15 special reference to the provision of novel grinding devices for the knife.

My invention consists in the combination, with the knife of the skiving-machine, of two grinding-disks or a single grinding-disk having 20 a grooved periphery and means for adjusting the said grinder and knife simultaneously; also, in the particular means herein shown for adjusting the grinder and knife and in novel means for operating the various 25 mechanisms or co-operative parts of the machine independently.

Figure 1 shows in side elevation a leather-skiving machine embodying this invention; Fig. 2, a front elevation of the machine shown 30 in Fig. 1; Fig. 3, a detail of a grinding device, to be referred to; and Figs. 4 and 5, sectional details, to be referred to.

The feed-roll A, secured to the shaft a, having its bearings in the main frame-work D of 35 the machine, the feed-disk B, secured to the shaft b, having its bearings in the bracket or arms b' of the frame-work, the revolving cutter C, secured to the shaft c, having its bearings in the frame c', the guide E, and presser 40 N are all as shown in the patent referred to.

A pulley a' is secured to the shaft a, by which it is revolved. A pulley b' is secured to the shaft b, by which it is revolved, and a pulley c' is secured to the shaft c, by which 45 it is revolved, said pulleys being connected by independent belts to a counter-shaft, thereby omitting a large number of gears and shafts now commonly used on the machine.

The grinding mechanism consists of two 50 abrasive disks e e', one of which has a feathered or chamfered edge to thereby present an annular groove or race for the cutter C, al-

though in lieu thereof it is obvious that a single abrasive disk may be formed with an annular groove. The disks e e' are secured to 55 a shaft e², having its bearings in a frame e³, secured to a bolt or stud e⁴, passing through a slot in the arm or frame of the machine, to which bolt or stud the frame or arm c', carrying the cutter, is also secured. The bolt or 60 stud e⁴, bearing both frames, has on it a washer e²⁰, having a pointed bearing-face formed by slabbing off or chamfering at each side, (see Fig. 4,) such pointed face permitting the washer to rock as the frames are 65 moved. The washer has a pin 2, which enters a groove in the bolt or stud, which serves to maintain the position of the washer on the bolt, a nut o being employed to force the washer against the frame of the machine. 70 By this construction it will be seen that the grinding disk or disks and the knife are simultaneously adjustable with relation to the other parts—i. e., whenever one is moved the other is correspondingly moved.

To move the knife and grinder simultaneously, as described, I have but to turn the screw c¹⁰ to move the frame c' on the hinge-connection or to loosen the bolt o² and turn the frames c' e³ on the pivot or stud e⁴. The 80 cutter and grinder are then moved simultaneously in a vertical arc, whereby their angle is changed and different bevel or bevels at various angles are obtained. As it is desirable to have the grinding-disks act sometimes 85 upon one and sometimes upon the other side of the cutter C, it is herein shown as vertically adjustable for this purpose. The means shown for accomplishing such vertical adjustment consists of a screw e⁵, turning in the 90 arm or bracket e⁶, said screw passing through a block e⁷, which embraces the shaft e² between the flanges e⁸ thereof, so that by turning the screw e⁵ by means of the hand-wheel e⁹ the said block e⁷ will be raised and lowered. In practice the grinding-disks e e' are 95 normally held in such position with relation to the cutter that the latter is not acted upon; but when it is desired to grind the cutter they are either raised or lowered, depending 100 on which side of the cutter it is desired to act. The pulley e⁹ is secured to the shaft e², by which it is revolved.

I claim—

1. In a leather-skiving machine, a work support and frame carrying both a revoluble circular cutter and grinder, and a horizontal pivot upon which said frame turns, so that
- 5 said cutter and grinder may be moved simultaneously in a vertical arc with relation to the work-support, substantially as described.
- 10 In a leather-skiving machine, a circular cutter and frame or arm carrying it, a grinder and a frame or arm carrying it, and a connecting bolt or stud for connecting the said frames or arms, whereby simultaneous movement of the cutter and grinder is effected horizontally and vertically, substantially as
- 15 described.
- 20 In a leather-skiving machine, the combination, with the circular cutter C and means for revolving it, of the grinding-disks $e\ e'$, one of which has a chamfered edge formed to present an annular groove to receive the edge of the cutter C, and a revoluble shaft carrying said grinding-disks, substantially as described.
- 25 In a leather-skiving machine, the revolving cutter C and grinding-disks, one of which has a chamfered edge formed to present an annular groove to receive the edge of the cut-

ter C, combined with a revoluble shaft carrying the grinding-disks and the pivoted arm supporting said shaft, substantially as described.

30 5. In a leather-skiving machine, the grinding-disks carried by a revoluble shaft, the revolving cutter C and movable frame carrying it intermediate said disks and means, substantially as described, for vertically adjusting said shaft, having its bearings in said frame to present one or the other of the surfaces of the cutter to the disks, substantially as and for the purpose set forth.

35 6. In a leather-skiving machine, pivoted frames carrying the cutter and grinder, and the grooved connecting bolt or stud upon which both of said frames rock, combined with the pointed or tilting washer, substantially as described.

40 In testimony whereof I have signed my name to this specification in the presence of two subscribing witnesses.

ANDREW J. TEWKSBURY.
